CEMENTING MACHINE

Arthur S. Johnson, Beverly, Mass., assignor to
United Shoe Machinery Corporation, Paterson,
N. J., a corporation of New Jersey

Application January 27, 1931. Serial No. 511,563

9 Claims. (Cl. 91—39)

This invention relates to cementing machines and is herein illustrated as embodied in a machine for the application of cement to the marginal portions of shoe soles.

In the manufacture of shoes in which the soles are secured to the uppers solely or primarily by means of cement, it is customary to apply a marginal stripe of cement to the flesh surface of the soles prior to bringing together the soles and the uppers. The cement, which usually is of the pyroxylin type, must be applied in liberal quantities, but, in view of the difficulty of removing drippings of cement accidentally applied to exposed portions of the soles, it is essential that the flow of cement shall be adequately controlled. It is also very desirable that the cement shall be applied in a stripe of uniform thickness. Furthermore, it is preferable to apply the cement by means of an applying member positioned above the work so that the operator can see what is going on and make sure of the proper operation of the machine without inverting the work. With this type of machine it is all the more difficult to control the cement and to avoid dripping on the work.

Accordingly, a primary object of the invention is to provide an improved cement applying machine in which the flow of cement can be adequately controlled and in which soiling of the work will be avoided.

With this in view, the illustrated machine, in accordance with an important feature of the invention, provides in a casing which surrounds a rotary applying member, cooperating control members associated with the same side of the periphery of the applying member within the casing and located one adjacent to the inlet of the casing and the other adjacent to the outlet thereof. The first of these controlling members regulates to a large extent the quantity of cement which is delivered to the applying member from an overhead cement pot from which cement flows by gravity into the casing. The second control member serves both as a spreader to even up the cement on the periphery of the applying member and as a control member to hold back within the casing such cement as is not removed from the applying member as, for example, during the intervals between the presentation of pieces of work. This second member is also provided with a portion coating with a lateral face of the applying brush to prevent the formation of a bead at the edge thereof.

In the use of pyroxylin cement it is customary to provide the operator with a small receptacle

containing solvent of any known kind in which spare applying members may be kept clean and any unremoved portions of cement prevented from hardening. Accordingly, another feature of the invention resides in the provision of a receptacle positioned on the machine beneath the applying member and provided with a cover which can be supported on this receptacle in an inclined position and arranged to catch drippings from the applying member and conduct them to the receptacle.

These and other features of the invention will be more fully described in the following specification taken in connection with the accompanying drawings, in which

Fig. 1 is a front elevation of the machine;

Fig. 2 is a side elevation thereof;

Fig. 3 is a detail in vertical section of a rotatable edge gage;

Fig. 4 is an enlarged view of the front of the applying member with the casing surrounding that member broken out to show the cement controlling members contained therein;

Fig. 5 is a side elevation on a still larger scale of the applying brush with the casing in section and showing a shoe sole presented thereto;

Fig. 6 is a detail plan view of a latch controlling a valve for regulating the flow of cement from the cement pot, and

Fig. 7 is a perspective view of the applying brush, removed from its casing, with one of the cement controlling members.

The illustrated machine is of the type shown in Letters Patent of the United States No. 1,778-184, granted October 14, 1930, on the application of J. W. Cosgrove, and, like that machine, has as its applying member a driven brush 10 mounted upon a shaft 12 which is supported in the upper half of a two-part frame 14, 15 and is arranged to be driven by an electric motor 16 in the direction indicated by an arrow in Fig. 4. The frame 14, 15 is carried at the upper end of a column 18 and at the top of the machine there is provided an overhead removable cement pot 20 which delivers cement through a delivery passage 22 in a casting 23 constituting part of the pot 20 to a casing 24 surrounding the brush 10. A slide valve 26 operated by a hand lever 28 opens or closes this passage 22. As in the patented machine, the frame is provided with an extension 30 having an overhanging hook 32 which cooperates with the lever 28 to prevent removal of the cement pot 20 unless the valve is closed. The illustrated machine has, in addition, a stop plate 34 cooperating with a flattened

extension 36 of the valve 26 to determine the maximum open position of the valve. The position of the stop plate 34 may be regulated by means of a hand screw 38. A spring latch 40 5 screwed to the under side of the stop plate 34 cooperates with a notch in the under side of the extension 36 to retain the valve in open position unaffected by any vibration of the machine. If it is desired to hold the valve in closed position, a screw 42 threaded through the rear end 10 of the lever 28 may be adjusted to the position shown in Fig. 6 to hold the valve closed.

The illustrated brush 10 differs from that shown in the patented construction in that it is provided not only with the usual bristles 44 but also has wire bristles 46 passed through suitable openings in the hub 48 and designed to have an abrasive action upon the margin of the shoe sole 50 to rough up the sole and bring the cement 20 into more intimate contact with the fibers of the leather and to allow the escape of air bubbles trapped in said fibers. It is rotated counterclockwise, as viewed in Fig. 4, so that it brushes against the surface of the sole 50 as the latter 25 is moved from right to left.

The casing 24 resembles that of the patented construction in that it is provided with an undercut tongue 52 (Fig. 5) which is received in a dovetailed slot 54 in the frame of the machine 30 but differs therefrom in substantial particulars. In the illustrated arrangement the casing is held detachably upon the frame by means of an end plate 56 secured to the tongue 52 and to the frame of the machine by suitable machine screws.

35 The casing 24 is in the form of a hollow casting closed by a removable end plate 58 and provided with an internal recess or passageway 60 (Fig. 4) in which the applying brush 10 is positioned. The casing has an inlet opening 62 communicating directly with the passage 22 and also has an outlet opening 64 through which the brush 10 projects and is exposed for the application of pieces of work to its under surface (Fig. 5). The hub 48 of the brush 10 fits closely within the 40 casing 24, compressing a felt washer 65, so as to prevent cement from flowing past said hub. The casing is provided with a cement controlling scraper 66 slidably mounted in the casing adjacent to the down-going side of the brush and 45 adjustable toward and away from the brush by means of a screw 68. This scraper 66 is in the form of a blade having a tapered outer end positioned close to the periphery of the brush at a point on the down-going side thereof just below the inlet opening 62. Another cement controlling blade or spreader 70 has a beveled edge 71 which cooperates with the periphery of the brush on the down-going side thereof at a point closely adjacent to the outer opening 64. This 50 blade is notched to provide a central portion which cooperates with the periphery of the brush and side arms 73 (Figs. 4 and 5) which cooperate with the lateral faces of the brush to prevent the formation of beads of cement at the edges 55 of the brush. The blade is positioned at an inclination to a radius of the brush at the point of intersection between the blade and the periphery of the brush, so that the ends of the bristles pass the central portion of the blade 60 without radical deflection thereof, and so that the cooperation of the arms 73 with the lateral faces of the brush is gradual and not abrupt as would be the case if these arms coincided with a radius of the brush. The position of this spreader 70 may be controlled by means of a screw 72 and

in practice the spreader is brought close to the brush bristles so that the cement carried by the brush is spread out into a uniform mass equal in thickness across the width of the brush. As long as the machine is in operation there is no tendency for cement to flow down past the up-going side of the brush because of the drag by the bristles of the brush and when the machine is stopped the valve 26 is closed, thereby shutting off the flow of cement.

When the machine is in operation, the upper scraper 66 holds back most of the cement which is descending from the cement pot and, owing to the friction of the revolving brush 10, the cement is caused to roll over and over just above the end of this scraper, as illustrated in Fig. 4. The action of the spreader 70 in spreading out the film of cement and in preventing the formation of beads at the edges of the brush has already been set forth. It can be seen, if a piece of glass is substituted for the end cover 58, that in intervals between the presentation of pieces of work there is stored up between the lower spreader 70 and the upper scraper 66 a small quantity of cement, as indicated in Fig. 4. When work is presented to the brush, this cement is used up rapidly and as soon as the presentation of work ceases then it begins again to accumulate in this space. There is always a thin film of cement upon the periphery of the brush from the point at which it leaves the spreader 70 around to the point at which it again meets the inlet openings 62 of the casing.

Partly because of the quick drying qualities of the pyroxylin cement usually employed and partly because of the desire to apply a liberal quantity of cement, it has been found particularly difficult to keep an ordinary fixed edge gage clean and in serviceable condition. Accordingly, the machine is provided with a rotatable edge gage 74 which 110 constantly presents a new surface to the advancing piece of work and which is kept clean by means of a cooperating scraper blade 76 which contacts with the side of the gage which is leaving the work. Preferably the gage is in the form 115 of a cylinder having a depending flange 78 and a hub 80 (Fig. 3), the flange 78 extending below the hub so as to protect a bearing 82 in which is carried a shaft 84 for supporting the gage and to keep the bearing free from cement. This cylindrical gage is secured to the shaft 84 for rotation in the direction indicated by an arrow in Figs. 2, 4 and 5, and about an upright axis substantially at right angles to the shaft 12 on which the applying member 10 is carried. The bearing 82 120 for the upright shaft 84 is part of a hollow casing 86 adjustably supported on the frame by means of a clamp nut 88. This permits the gage to be moved toward and away from the applying member to bring the stripe of cement in exactly 125 the desired relation to the margin of a sole 50 (Fig. 5). Within the hollow casing 86 are mitre gears 90 connecting the upright shaft 84 to a horizontal shaft 92 which is joined by a screw-and-slot connection 94 (Fig. 3) to a stub shaft 96 130 having a tongue 98 arranged to enter a corresponding slot in the end of a shaft 100, provided in the patented machine as a jack shaft carrying reducing gears 102 between the motor 16 and the driven shaft 12. A spring 104 between the hollow 135 casing 86 and the end of the stub shaft 96 holds the latter firmly in contact with the end of the shaft 100 and facilitates adjustment in and out when the nut 88 is loosened. A removable cover 140 106 is provided for the end of the hollow casing 86, 150

thus facilitating assembly of the device and the exclusion of cement. This gage and its mounting are not claimed herein since they are claimed in a copending application Serial No. 511,808, filed 5 Jan. 28, 1931, in my name.

In order to prevent the cement on the brush 10 from hardening when the machine is left idle for a considerable period of time, such as overnight, there is provided a removable cup-shaped 10 cover 110 which may, if desired, contain a small amount of solvent for the particular cement and which at any rate will exclude air from the brush and keep the same soft and in a workable condition. To facilitate the application of this cover 15 after the gage nut 88 has been loosened and the gage moved back out of the way, the casing 24 is provided with undercut grooves 112 and 114 (Fig. 5) and the upper edges of the sides of the cover 110 are inturned (Fig. 2) and arranged to 20 snap into said grooves for frictional engagement with the casing when the cover is applied to the casing.

Although the arrangement for controlling the cement on the applying member is highly efficient, 25 it nevertheless is found practically impossible wholly to eliminate dripping, and I have therefore provided an arrangement for catching such slight dripping as may occur, thereby to avoid soiling the floor of the room in which the machine is used. For this purpose, as well as for others to be explained, there is provided a receptacle 120 detachably mounted on a U-shaped bracket 122 secured to the frame 15 by means of 30 hooks 121 on the receptacle and is held by a wing nut 123. This receptacle is provided with a cover 124 which is hinged upon a pin 126 and the receptacle is provided with a lug 128 arranged to support the cover 124 in inclined position, as shown in Fig. 2, with the cover directly beneath 35 the applying brush 10 so as to catch drippings therefrom and constructed and arranged to conduct these drippings into the receptacle 120. This receptacle may be partially filled with solvent, if desired, and utilized as a storage place for the cover 110 or for spare brushes (not shown) which 40 may be substituted for the brush 10 on the machine. To make it more satisfactory for this purpose, there has been provided a removable 45 rack 130 which will hold the immersed parts out 50 of the thicker part of the liquid such as may result from the drippings conducted to the receptacle by the cover 124. This rack is provided with an upstanding handle 132 by means of which the immersed parts may be lifted out of the liquid 55 for use by the operator or when it is necessary to clean out the receptacle.

For the convenience of the operator, the machine preferably is also provided with a work table 134 clamped to a horizontal bar 136 which, 60 in turn, is clamped to an upright bar 138 adjustably held in a bracket 140 by means of a collar 142 and a set-screw 144. This bracket 140 reaches half way around the supporting column 18 and is provided with lateral lugs 146 which cooperate 65 with similar lugs upon a bracket 150 in the other side of the column to receive clamp screws 148. The brackets 140 and 150 have depending feet 152 which bear against the sides of the column and by proper adjustment of the screws 148 the 70 brackets 140 and 150 may be brought into level position regardless of the exact dimensions of the column or the position of the brackets thereon. On the other side of the machine there is a similar arrangement of bars 154 and 156, this latter bar 156 being received within a clamp 75

on the under side of a rack holder frame 160. This frame may be used to support a wire rack 162 of the type illustrated and designed to receive cemented soles 50 or to receive wooden racks or pipe racks of the types found in shoe factories and used for a similar purpose. To this end, the rack frame 160 has adjustable lugs 166 which operate with pivoted jaws 168 in clamping one side of the rack 162. The jaws 168, pivoted on fulcrum pins 169, are spring-pressed toward the rack by coil springs 170 the tension of which may be adjusted by screws 172.

In the use of the machine, supposing that the pot 20 is full of cement and that the operator has provided himself with a stack of work (not shown) on the table 134, he will remove the cover 110 to expose the brush and deposit it in the receptacle 120, and then will adjust the edge gage 74 into the desired relation to the brush by loosening and tightening the wing nut 88. He then will open the valve 26 by movement of the lever 28 and, if necessary, will adjust the cement controller 66 and the spreader 70 to provide just the desired amount of cement on the brush for application to the work. Soles 50 may then be passed beneath the brush from right to left, as viewed in Fig. 4, their progress being helped by the rotary gage 74 until the margins have been coated, whereupon each sole will be deposited in the rack 162 to dry. The cement 100 coatings are later revived as the soles are embodied in shoes.

Having described my invention, what I claim as new and desire to secure by Letters Patent of the United States is:—

1. In a cementing machine, a casing having openings at the top and bottom, an applying member rotatably mounted within said casing and projecting through the bottom opening for contact with pieces of work presented thereto, means for supplying cement to the upper opening of said casing, a cement controlling member in said casing cooperating with the periphery of the applying member on one side and adjacent to the upper opening of the casing, and another cement controlling member coacting with the periphery of the applying member on the same side of the casing and adjacent to the lower opening of the casing.

2. In a cementing machine, a casing open at the top and bottom, a driven rotatable applying member substantially filling said casing and projecting through the bottom opening for contact with pieces of work presented thereto, means for supplying cement to the upper opening of the casing, a cement controlling scraper adjustably mounted in said casing with its edge adjacent to the downgoing side of the periphery of the applying member as said periphery passes the upper opening of the casing, and a cement controlling spreader contacting with the downgoing side of the periphery of the applying member as the latter emerges from the casing.

3. In a cementing machine, a casing open at the top and bottom, a driven rotatable brush substantially filling said casing in a direction parallel to the axis thereof, a cement controlling scraper adjustably mounted in said casing and cooperating with the downgoing side of the brush at a point just below the upper opening in the casing, and a cement controlling spreader contacting with the downgoing periphery of the brush adjacent to the outlet opening of the casing, said adjustable members and the casing

forming a pocket storing up cement unremoved from the applying brush by the presentation of work.

4. In a cementing machine, a driven rotatable cement applying brush having a flexible applying portion, means for supplying cement to the upper face of said brush, a casing partially surrounding the brush and leaving the lower face thereof exposed for the presentation of work, and a cement controlling member associated with the down-going side of the brush having one portion cooperating with the periphery of the brush and another portion cooperating with a lateral face of the flexible portion of the brush, said latter portion serving to prevent the formation of a bead of cement at the edge of the brush.

5. In a cementing machine, a driven rotatably mounted applying brush having a hub and bristles extending therefrom, means for supplying cement to an upper portion of said brush, and means for controlling the cement applied by the lower face of the brush to a piece of work comprising a blade disposed at an inclination, to a radius of the brush at the point of intersection between the edge of the blade and the periphery of the brush, said blade being notched and provided with outwardly extending arms coacting with the lateral faces of the bristle portion of the brush to prevent the formation of beads of cement at the edges of the brush.

6. In a cementing machine, a casing open at the top and bottom, a driven brush having an applying portion and rotatably mounted within said casing and projecting through the bottom opening for contact with pieces of work presented thereto, means for supplying cement to the upper opening of said casing, a cement controlling member in said casing cooperating with the periphery of the applying member on the downgoing side thereof adjacent to the upper opening of the casing, and another cement controlling member coacting with the applying member on the down-going side thereof at a lower point in the casing.

having a portion associated with the periphery of the brush and another portion associated with the lateral face of the applying portion of the brush to prevent the formation of a bead at the edge of the brush.

7. In a cementing machine, a cement applying member exposed at its lower side for the presentation of work thereto, an overhead receptacle supplying cement to the upper side of said member, another receptacle mounted on said machine at a substantial distance below said applying member, a cover for said latter receptacle, and means for supporting said cover in inclined open position directly beneath said applying member, said cover being constructed and arranged when the cover is in inclined open position to drain into the latter receptacle the drippings from the applying member.

8. In a cementing machine, a rotary cement applying member, means for supplying cement to the upper side of said member, the lower side of said member being exposed for the presentation of the work thereto, a receptacle mounted on said machine and positioned to the rear of said applying member, said receptacle having a hinged cover positioned, when open, directly beneath said applying member, and means for supporting said cover in inclined open position to catch the drippings from the applying member and lead them into the receptacle.

9. In a cementing machine of a type liable to dripping from an applying member to the under side of which work may be presented, a receptacle for the reception of disconnected machine parts and adapted to contain cement solvent, said receptacle being positioned below said applying member and provided with means to catch drippings from the applying member and conduct them to the receptacle, and a screen in said receptacle spaced from the bottom thereof to support the machine parts out of contact with accumulated drippings of cement.
